UNITED STATES PATENT OFFICE.

JOSEPH WILLIAM HIGGS, OF SHARON, PENNSYLVANIA.

ROLL FOR ROLLING CAR-COUPINGS.

SPECIFICATION forming part of Letters Patent No. 289,001, dated November 27, 1883.

Application filed May 16, 1883. (No model.)

To all whom it may concern:

Be it known that I, JOSEPH W. HIGGS, of Sharon, in the county of Mercer and State of Pennsylvania, have invented certain Improved 5 Rolls for Rolling Railroad-Car Coupling-Pins; and I hereby declare the following to be a full, clear, and exact description of the same, reference being had to the accompanying drawings, making part of this specification, in 10 which—

Figure 1 is a side elevation of the rolls with the dies registering. Fig. 2 is a side elevation with rolls given a quarter-turn from the position shown in Fig. 1. Figs. 3, 4, and 5 illustrate the coupling-pin blanks before cutting, 15 also sections on lines *x x* and *y y*.

The object of my invention is to roll blanks to be subsequently cut into railroad-car coupling-pins; and my invention consists in the 20 particular construction of rolls I employ to roll these blanks.

In order that those skilled in the art may make and use my invention, I will proceed to describe the exact manner in which I have carried it out.

In the said drawings, A represents the upper roll, and A' the lower roll, provided with grooves *a a'*, *b b'*, *c c'*. The groove *a a'* is provided, if desired, merely to bring the bars to a 30 uniform diameter before passing them through either grooves *b b'* or *c c'*. In the edges of grooves *b b'* are inserted pins *d d'*, with their ends slightly projecting from the surface of the grooves. Alongside of each projecting 35 end of the pins *d d'* is a semi-conical depression, *e e'*, with its greatest depth next to the pin, so that when the depressions in the upper and lower rolls register, the space within the

depressions represents a short cone. When the hot bar is passed through the rolls in 40 groove *b b'*, the pins *d d'* at each revolution displace a portion of the hot metal and squeeze it into the depressions *e e'*, thereby forming two studs or projections, *f f'*, on the blank B at regular intervals of a proper length to 45 cut the pins. The blank is then cut at about the points *i i'*, forming a cheap but perfectly-operating coupling-pin.

When it is desired to have four projections on the pin to form a head, I use the grooves *c c'*, where the pins *g g'* are located slightly within the edges of the grooves and project to a somewhat greater extent than pins *d d'*, and behind each pin within the groove is a conical-shaped depression, *l l'*, and each pin *g g'* displaces enough metal to fill each depression *l l'*, and thus form projections or studs *s s'* on the blank E. (See Fig. 4.)

I am aware it is not new to roll railroad coupling-pin blanks with heads at intervals, 60 and then divide the blanks into proper lengths; and I am also aware that rolls have been cast with inequalities to produce such result; and hence I make no broad claim to such devices; but,

Having thus described my invention, what I claim as new, and desire to secure by Letters Patent, is—

The rolls A A', provided with grooves, having pins inserted in the faces of said grooves, 70 and depressions cut in the rolls adjacent to the inserted pins, as set forth.

JOSEPH WILLIAM HIGGS.
